UNITED STATES PATENT OFFICE

SAMUEL N. HOPE, OF WAUWATOSA, WISCONSIN, ASSIGNOR TO GRIFFITH-HOPE COMPANY, OF WEST ALLIS, WISCONSIN, A CORPORATION OF WISCONSIN

CARD HOLDER

Application filed June 1, 1931. Serial No. 541,378.

The invention relates to card holders and has for an object the provision of a simple, inexpensive and compact holder adapted to be mounted on the instrument board of an automobile and including a rotatably mounted transparent card container for protecting and displaying a registration card therein, the holder being constructed to permit sealing for deterring unauthorized access to the card.

The invention further consists in the several features hereinafter set forth and more particularly defined by the annexed claims.

In the accompanying drawings
15 Fig. 1 is a top plan view of a card holder embodying the invention as it appears when mounted on a support;

Fig. 2 is a longitudinal sectional view of the holder;

20 Fig. 3 is a fragmentary view of an end portion of the holder, and

Fig. 4 is a transverse sectional view taken on the line 4—4 of Fig. 2.

In these drawings, the numeral 10 designates a sheet metal frame having a flat narrow base portion 11 and laterally extending parallel ears 12 formed integrally therewith and constituting end walls. The base portion 11 is adapted to abut against an instrument panel 13 of an automobile and is secured thereto by screws 14.

A tube 15 of resilient transparent material, such as celluloid, extends between the end walls 12 of the holder frame and has its end portions rotatably mounted between pairs of spaced inturned arcuate flanges 16 which are integrally formed on the respective end walls and which engage the exterior surface of the tube. The transparent tube receives therein a rolled card 17, which in the present instance is indicated to be an automobile registration card. The rolled card, after insertion into the tube, remains in engagement with the inner surface of the tube, as seen in Fig. 4. The tube is installed or removed by compressing it diametrically so that it will pass between the spaced flanges 16. The tube, after insertion, returns to its cylindrical shape and fits against the inner faces of the flanges 16.

After the card-holding tube is thus mounted in place, a flat sheet metal key 18 is passed through the tube and through aligned slots 19 formed in the opposite end walls 12, the slots being perpendicular to the base. One 55 end of the key is provided with a head 20 and the other end is provided with a slot 21, which is adapted to receive a seal 22, thus preventing removal of the key and card-receiving tube except by breaking the seal. The seal 60 may bear thereon a number corresponding to the registration number of the automobile, if this is required by law. If a seal is not required the seal and key may be omitted.

By reason of its compact construction the 65 holder requires only a small space on the instrument panel or other support on which it is mounted, while the card may be readily examined by rotating the transparent tube.

What I claim as new and desire to secure 70 by Letters Patent is:

1. A card holder comprising a frame including spaced walls having bearing surfaces thereon, a transparent card-receiving tube extending between said walls and rotatably 75 mounted on said bearing surfaces, and a key extending through said walls and within said tube and having a seal-receiving opening at one end.

2. A card holder comprising a frame having a base portion and a pair of spaced end walls, a pair of spaced inturned arcuate flanges formed on each of said end walls, and a resilient transparent card-receiving tube extending between said end walls and rotatably 85 mounted on said arcuate flanges, said tube being diametrically compressible to pass between said flanges.

3. A card holder comprising a frame having a base portion and a pair of spaced end walls having aligned slots therein, inturned arcuate flanges formed on said end walls, a transparent card-receiving tube extending between said end walls and rotatably bearing 95 on said arcuate flanges, and a flat headed key extending through said slots and within said tube.

4. A card holder comprising a frame having a base portion and a pair of spaced integrally formed ears, inturned arcuate flanges 100

integrally formed on said ears, and a transparent card-receiving tube extending between said ears and rotatably bearing at its periphery on said arcuate flanges.

5. A card holder comprising a frame including spaced walls having bearing surfaces thereon, and a resilient transparent card-receiving tube extending between said walls and rotatably mounted at its periphery on
10 said bearing surfaces, said tube being deformable to permit its application to said bearing surfaces.

6. A card holder comprising a frame having a base portion and a pair of spaced end walls, inturned arcuate flanges formed on said end walls, the flanges on at least one of said end walls being discontinuous to present a gap, and a resilient transparent card-receiving tube extending between said end walls
26 and rotatably mounted on said flanges, said tube being deformable to pass through said gap.

In testimony whereof, I affix my signature.
SAMUEL N. HOPE.
